CAST CUTTER

Harry T. Treace, Forest Hill, Tenn., assignor to Richards
Manufacturing Company, Inc., Memphis, Tenn.

Filed May 8, 1974, Ser. No. 468,094

Term of patent 14 years

Int. Cl. D24—02

U.S. Cl. D83—12 R

FIG. 1

FIG. 2

FIG. 3

FIG. 4

FIG. 5

FIG. 6

FIG. 7

FIG. 8

FIG. 1 is a top view of a cast cutter, showing my new design;

FIG. 2 is an end elevational view thereof;

FIG. 3 is an end elevational view thereof from the opposite end from that shown in FIG. 2;

FIG. 4 is a side elevational view thereof;

FIG. 5 is a side elevational view thereof from the opposite side from that shown in FIG. 4;

FIG. 6 is a bottom plan view thereof;

FIG. 7 is a perspective view thereof from the front and top of FIG. 1; and

FIG. 8 is a perspective view thereof as seen from the bottom and rear of FIG. 1.

I claim:

The ornamental design for a cast cutter, substantially as shown and described.
